UNITED STATES PATENT OFFICE.

LESTER KIRSCHBRAUN, OF CHICAGO, ILLINOIS, AND CHESTER R. MACDONALD, OF MIDDLETOWN, OHIO; SAID MACDONALD ASSIGNOR TO FLINTKOTE COMPANY, OF BOSTON, MASSACHUSETTS, A CORPORATION OF MASSACHUSETTS.

APPARATUS FOR APPLYING WATERPROOFING MATERIAL TO SHEETS.

Application filed March 9, 1925. Serial No. 13,995.

This invention relates to improvements in apparatus for applying waterproofing material to sheets, and refers more specifically to a specific type of roll utilized for applying a waterproofing material, for instance in emulsion or suspension form to the surface of wet plies of paper formed on a multicylinder paper machine, or for the purpose of applying such waterproofing material whether in emulsion form or not, to the surface of fabric or other sheet material whether wet or dry.

It has been found in actual use that the specific type of application roll described in the following specification possesses many advantages, among which may be cited the uniformity with which it is possible to apply a liquid film of waterproofing material to a wet or dry sheet, thus resulting in the use of a minimum amount of waterproofing material and uniform distribution throughout the final product.

In the specific embodiment of the present invention, the roll consists of a cylinder core upon which is arranged a number of spirally wound wires. Spaced transversely across the surface of the roll and disposed upon the spiral winding wires, are a plurality of spacing or backing rods. A screen of suitable wire mesh is wound about the outside of the backing rods. The entire construction just described, forms a unit adapted to be rotated in a bath of the waterproofing liquid, the screen being adapted to contact the surface of the sheet to which it is desired to apply the liquid waterproofing material.

In a previous application filed by me, Serial No. 582,303 filed on August 6th, 1922, the general process of applying emulsion has been set forth.

This earlier application discloses a variety of alternate methods of roll application whereby in some instances a wooden or solid roll is employed, and as another alternative, a wire covered roll is employed.

Practical commercial operations have shown that while the solid rolls can be used particularly with heavy paper, there is always a danger that these rolls may pull the wet delicate web away from the blanket. It has also been found that the amount of emulsion that can be carried on the surface of a smooth solid roll, is not in all cases suffi-

cient to produce the desired moisture-proofing effect. With the wire covered roll of the present invention however, it is possible to apply the waterproofing material in larger quantities, better regulated, and in a much more uniform manner.

In commercial operation, with a wire covered roll in which the wire facing was applied directly to the solid core, it was found that there would be a tendency for the emulsion to be concentrated in streaks, even when the wire surface was spaced somewhat from the solid core by means of circumferentially arranged spacing wires. There would be a tendency for a drop or stream of the emulsion to follow the spacing wire and cause a heavier deposition of emulsion on those portions of the sheet opposite to the contacting surface at these points. The result was to produce a sheet in which there appeared a plurality of longitudinal streaks in which of course, there was a heavier deposition of the waterproofing material. On the heavier paper, this did not make much difference, but on lighter paper when the product was passed through the calenders, the difference in caliper due to the elevation of the streaks would cause calender pressure to be concentrated upon these high points, producing a streaked final product.

The moisture-proofing value obtained was not at maximum efficiency, as a much larger amount of waterproofing emulsion was required to be used than if the emulsion was applied uniformly.

Careful observation of the operation of both the solid rolls and wire covered rolls indicated that the cause of this streaking was due to the suction between the wet web and the surface of the wire covered roll, that is, as the wet sheet left the roll, there was a certain amount of cohesion due to suction which concentrated a surface of waterproofing emulsion into a continuous droplet, which latter would persist in the nip between the sheet and the following side of the roll. The roll of the present application was designed to obviate this difficulty.

In the drawings, Fig. 1 is a top plan view partly in section of my invention. Fig. 2 is a cross sectional view on line 2-2 of Fig. 1. Fig. 3 is an enlarged cross sectional view of the roll.

Referring in detail to the drawings, 1

- designates a vat having the transverse partition walls 2, and provided with a longitudinal baffle 3 held in place by means of the lugs 4. Inlets 5 controlled by valves 6 discharge water into the end compartments formed by means of the transverse partitions 2, the use of which will be herein-after explained. Emulsion which may be prepared in accordance with my issued 10 United States Patent No. 1,302,810, may be introduced through the pipe 7 and discharged into the interior of the inner compartment between the two transverse partitions 2 through the perforations 8. The 15 amount of the emulsion introduced through the pipe 7 is carefully regulated.

The roll designated as a whole 9, is mounted on shaft 10, which shaft is provided with the bearings 11 in the exterior side walls of 20 the box 1, and with the bearings 12 in the transverse partitions 2. The shaft projects beyond one end of the side wall of the box 1, and is provided with the cone 13, the exterior of the shaft 10 being provided with 25 the bearing 14. An endless belt or pulley 15 contacts the surface of the cone 13, which belt or pulley also contacts the surface of an oppositely disposed cone 16, providing a standard type of changed speed. The lever 30 17 is provided which may be manually manipulated for changing the speed of the shaft 10 during the operation. The pulley 16 is mounted on the shaft 18 which has bearings 19, and provided interior the bearings 35 with the pulley wheel 20 and belt 21 communicating with any source of driving power, preferably in coordination with the paper machine.

Referring now more particularly to Figs. 40 1 and 3, in the present instance, the shaft 10 is shown as being surrounded with the core 22. On the exterior surface of the core 22 are arranged a series of spirally wound wires 23. Transversely of the circumference of the cylinder 22 and superposed on top of the wire 23, are a plurality of uniformly spaced rods 24 over which is adapted to be spread a screen 25 of suitable wire mesh. We have found 14 mesh wire to be 45 generally satisfactory. The rods 24 are 50 preferably rectangular in shape, so that their contact with the surface screen 25 is only upon the smallest point. Otherwise, there would be a tendency for an excess of 55 liquid to collect in the meshes of said screen at the point of contact between the supporting surface and the screen itself.

The dam 3 may be composed of a plurality of pieces, and the level of the emulsion 60 maintained in the vat or box may be thus controlled. An excess is withdrawn through the outlet 26. As shown specifically in Fig. 2, the wet web designated as 27, carried on blanket 27' which has just been formed on a 65 cylinder mold is fed upwardly and the

screen surface 25 of the roll 9 lightly contacts the under surface of said wet web to apply the liquid waterproofing material thereon in a uniform film.

The roll 28, the tension of which is adjustable by means of the screw 28', is provided to insure light and constant contact. A layer of such waterproofing material is designated at 29.

The purpose of the present invention is 75 effected not only by the spacing away of the screen 25 from the core so as to permit free access of air to the under side of said screen 25, but also to the particular positioning of the winding wires 23 and rods 24. The effect of the spiral winding of the wires is to cause an even distribution of the emulsion and the transverse positioning of the rods 24 breaks up any tendency to streak formation. It is apparent that if the supporting 80 surface should be circumferentially disposed about the core, there would be a tendency for the continuous formation of a streak, whereas, if the supporting surface is arranged transversely of the core, the tendency 85 to streak formation is interrupted, as there is no continuous circumferential point or path of contact.

Another feature of the present invention is the provision of mechanism for maintaining the bearings in a satisfactory operating condition, which is accomplished by maintaining a pool of water in the end compartments 30 formed in the vat 1 by means 90 of the transverse partitions 2. This pool 100 of water is maintained at a somewhat greater elevation than the emulsion inside the compartment 31 of the vat, in order that a slight trickle of water may penetrate the bearings 12 into the emulsion, keeping those 105 bearings clean, whereas, if the liquid level in the compartments 30 was lower than the level in compartment 31, the emulsion would penetrate through the bearings 12 in an opposite direction, resulting in the bearings 110 being broken down due to frictional contact, which causes same to stick and dry.

It is understood of course, that the emulsion may be introduced in any suitable manner to the compartment 31. It is obvious 115 of course, that increasing the height of the dam 3, the liquid level in the compartment 31 is increased, resulting in applying increased amounts of emulsion to the surface of the roll. It is obvious of course, that 120 instead of using a solid core which is preferable, a hollow roll somewhat like a dandy or spider roll can be utilized, so long as the scheme of spacing of the spiral winding wires and backing rods, is carried out.

We claim as our invention:

1. Apparatus for applying waterproofing liquid to sheets, comprising a core mounted on a rotatable shaft, winding wires disposed circumferentially around the core, 130

- spacing elements superposed on the winding wires and extending in a direction substantially transverse of the core and a sheet of wire mesh disposed on the exterior of said spacing elements. 25
2. Apparatus for applying waterproofing liquid to sheets, comprising a core mounted on a rotatable shaft, winding wires spirally disposed circumferentially around the core, 30
- 10 angular spacing elements superposed on the winding wires and extending in a direction substantially transverse of the core and a sheet of wire mesh facing disposed on the exterior of said spacing elements, said angular elements so arranged that they contact the wire mesh facing at their apex. 35
3. Apparatus for applying waterproofing liquid to sheets, comprising a solid core mounted on a rotatable shaft, winding wires disposed circumferentially around the core, 40
- 20 spacing elements superposed on the winding wires and extending in a direction substantially transverse of the core and a sheet of wire mesh disposed on the exterior of said spacing elements.
4. An apparatus for applying waterproofing liquid to sheets, comprising a support mounted on a rotatable shaft, non-meshed winding wires disposed circumferentially around said support, spacing elements superposed on the winding wires and disposed at an angle to the winding wires, and a foraminated facing disposed on the exterior of said spacing elements. 45
5. An apparatus for applying waterproofing liquid to sheets, comprising a support mounted on a rotatable shaft, non-meshed winding wires disposed circumferentially around said support, spacing elements superposed on the winding wires, and a foraminated facing disposed on the exterior of said spacing elements, said spacing elements being angular in cross section and disposed so that they contact a foraminated facing on an edge. 50
